[57] CLAIM

The ornamental design for a compact camera, as shown and described.

DESCRIPTION

FIG. 1 is a front, top and left-side perspective view of a compact camera showing our new design;

FIG. 2 is a rear, top and left-side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side view thereof;

FIG. 8 is a right side view thereof; and,

FIG. 9 is a view from the same perspective as in FIG. 1, in which a lens protector is closed and a flash device is inside of a camera body.
